UNITED STATES PATENT OFFICE

126,715

DESIGN FOR A TRAVELING BAG

Charles Doppelt, Chicago, Ill.

Application August 3, 1940, Serial No. 94,200

Term of patent 7 years

To all whom it may concern:

Be it known that I, Charles Doppelt, a citizen of the United States, residing at Chicago, in the county of Cook and State of Illinois, have invented a new, original, and ornamental Design for a Traveling Bag, of which the following is a specification, reference being had to the accompanying drawing, forming part thereof.

Fig. 1 is a perspective view of a traveling bag showing my new design. The end not shown is similar to that shown.

Fig. 2 is a perspective view of same in partially opened position.

I claim:

The ornamental design for a traveling bag, as shown and described.

CHARLES DOPPELT.
